Specification of Letters Patent. Patented Jan. 15, 1918.

Application filed June 20, 1912. Serial No. 704,782.

To all whom it may concern:

Be it known that I, CHARLES T. RAY, a citizen of the United States, residing at Louisville, in the county of Jefferson and 5 State of Kentucky, have invented new and useful Improvements in Cultivators, of which the following is a specification.

This invention relates to improvements in soil tillage implements and particularly to 10 cultivators of the straddle-row type, and it consists in various novel features of the construction and correlation of parts substantially as hereinafter described and particularly pointed out in the subjoined claims: 15 whereby the tillage elements may be readily and quickly adjusted to meet widely varying and a maximum number of different conditions in respect of their relative positions and their number.

20 In the accompanying drawings, the at present preferred detail embodiments of the several parts forming the present invention are illustrated, but it is to be understood that these detail embodiments are merely 25 exemplary of means now considered to be best adapted to carry the purposes of the invention into practical effect, and that other detail embodiments than those illustrated and hereinafter described may be resorted to.

30 In the drawings:—

Figure 1 is a perspective view of said preferred embodiment of the invention.

Fig. 2 is a plan view of the same.

Fig. 3 is a rear end view, with some parts 35 in elevation while others are broken away, and still others are in section.

Fig. 4 is a detail section on the line 4—4 of Fig. 2.

Fig. 5 is a detail section on the line 5—5 40 of Fig. 4, through only the beam and sleeve, the rear end of the coupling being omitted.

Fig. 6 is a detail sectional view on the line 6—6 of Fig. 2.

Fig. 7 is a detail plan view of the saddle, 45 casting and

Fig. 8 is a detail of the axle collar.

Fig. 9 is a sectional detail view of the cross head.

Like characters of reference denote like 50 parts in the several views.

The illustrated embodiment of the invention will be described somewhat restrictively

in detail, but it is not intended thereby to limit the parts to the restrictively-described forms thereof, the parts being particularly 55 described only in order that the best form of the invention may be disclosed, other forms and arrangements of parts being within the scope of the invention, and in a measure at least, capable of carrying the 60 purposes into practical effect.

To a saddle A, hereinafter described, on the underside of the beam B the inwardly extending ends 10, 10 of the arch members 11, 11 of the axle are connected in such manner as to permit said members conveniently 65 to be adjusted relatively to each other and fixedly held in their adjusted position, the adjustment referred to serving to vary the distance between the carrying wheels C C 70 which are mounted on outwardly-extending extremities 12, 12 of the axle, as usual. From their said outwardly-extending extremities each axle member extends forwardly as shown at 13 and thence inwardly, 75 as shown at 14, to the lower end of its arch member 11.

Top and bottom evener arches, marked D and D' respectively, are suitably secured as 80 shown at 14' to the upper and under sides of the beam B, and between the depending sides of these arches evener members E and E' are pivoted, as shown at 15. The upper ends of the evener members are connected by links 16, 16 to opposite ends of a cross 85 plate 17 which is pivoted at 17' to the beam B. Diagonal braces 18, 18 whose forward ends are arranged between the evener arches and are suitably secured to the bottom arch D' at 19, 19, extend from said arches back 90 to the beam B, to which their rear ends are suitably secured at 20.

F and F' designate the gang beams. Couplings G G' are secured to the front ends 95 of these beams and project forwardly therefrom. The forward end of each of these couplings is provided with upper and lower arms 21 and 22 arranged respectively above and below the portion 14 of the corresponding axle member. One of the arms, as 21, of each coupling has a socket 23 which is tapered for a portion of its length, (see Fig. 4), while the other arm of each coupling 100 has a tapered opening 24 within which there

is fitted a hollow externally-tapered plug 25 which for a portion of its length is internally tapered in a direction the reverse of the taper of the socket 23, said internally tapered portion of the plug forming a socket 26. Upon the portions 14 of the axle members are sleeves 27 having openings 28 alined with the sockets 23 and 26 of the respective couplings. 29 (Fig. 4) designates a hollow post. There is one such post for each beam, and each post has tapered ends. The tapered ends of one of these posts are seated in the sockets 23 and 26 of coupling G, and the tapered ends of the other are seated in like sockets of the coupling, G'. Suitable means, (as bolts 30, extending through the hollow posts 29 and plugs 25 and to the outer surfaces of the arms 21, 22) hold the parts together.

20 The plugs 25, containing the sockets 26, being removably fitted to openings in the couplings, permit the parts to be readily assembled and taken apart, and the tapered surfaces of the posts and sockets afford adequate provision for the taking up of wear. Preferably, one end of each plug protrudes, as shown at 25^a, from the arm 22 of its coupling and this protruding part is of suitable form, as square, to engage an appropriate tool for inserting it into or removing it from the opening 24.

25 The posts 29, are respectively connected to members 14 of the axle through the medium of sleeves 27, having openings 28, through which the posts extend.

Accordingly, it will be seen that the couplings G, G' are freely movable pivotally at their front ends on substantially vertical axes—*i. e.* around the posts 29, respectively—40 and that the gang beams F, F' partake of this movement. In other words, the beams are mounted to have free swinging movement on substantially vertical axes arranged in advance of their forward ends.

45 Provision also is made for a relative adjustment vertically of the sleeves 27 and the posts 29, this adjustment varying the height of the forward ends of the beams which, as already shown, are connected with the posts through the medium of the couplings. To this end, each of the sleeves 27 is provided rearward of its opening 28 with flanges 31 which form rearwardly projecting lips on opposite sides of the adjacent post 29, and suitable means, as bolts 33 extending through openings 34 in the lips or flanges and having appropriate nuts, are employed to draw the lips or flanges together and hold them, to thereby clamp the sleeves and posts together. Obviously, when the nuts on the bolts 33 have been slackened, the clamping effect referred to will cease, and a relative adjustment of the beams and sleeves may then be effected, which will vary 60 the height of the forward ends of the beams

with reference to the ground and hence vary the depth of penetration of the tillage elements on the beams.

In the form of the invention herein exemplified the axle comprises, as already stated, two arch members 11, from the lower ends of which members 14 extend outwardly to other members 13 which have, at their ends opposite the members 14, lateral projections 12 upon which the wheels C, C are 70 rotatably mounted. This particular construction enables the wheels C, C to be moved forward or back relatively to the beam B, primarily for balancing purposes, as will be well understood. It will be noted that in the movement of the wheels forward from or rearward toward the positions shown in Fig. 1, the axle portions 13 move forward or rearward as the case may be, pivotally on an arc struck from the axle portions 14. In this movement the portions 14 move pivotally in the sleeves 27 and are raised or lowered bodily, according to whether the movement of the portions 13 is forward or rearward. If at this time, the sleeves be 75 clamped to the posts 29, the latter, and consequently the front ends of the beams F also, will be raised or lowered: and if this raising or lowering of the beams be not desired, then the bolts 33 should be slackened, in 80 which event the sleeves 27 may move, with the axle portions 14, up or down upon the posts 29, if at this time the front ends of the beams be otherwise supported, as by the hands for example. Of course, the posts 29 may be raised or lowered in the sleeves 27 whenever this is necessary or expedient in 85 the adjustment of the front ends of the beams to predetermined height from the ground. It is not essential to the invention 90 that the axle comprise the portions 13.

The sleeves 27 are preferably open along their forward longitudinal sides for convenience in inserting them upon and removing them from the axle members—the members 14, for example,—to which they are applied: and they are provided with blocks 35 which are inserted between their upper and lower members and are suitably secured in place, as by the bolts 36 for example. These 100 blocks have concave inner surfaces to conform to the surfaces of the axle portions which they engage. This construction provides for pivotal movement of the axle within the sleeves and also enables the sleeves to 105 be most conveniently and quickly mounted upon said axle-ports. Preferably, the blocks are spaced apart and arranged at the ends of the sleeves, and preferably also the upper and lower members of the sleeves are 110 reduced in width between said blocks, to lighten the structure. The sleeves are also provided with downwardly and rearwardly extending arms 37, to which the lower ends 115 of springs H, H are secured, the upper ends 120 of which are secured to the axle members. The 125 sleeves are also provided with downwardly and rearwardly extending arms 37, to which the lower ends of springs H, H are secured, the upper ends 130

of said springs being attached to threaded rods by which they are connected to brackets H' clamped to the portions 11 of the axle-members, the said rods being adjustable with relation to the brackets to thereby adjust the tension of the springs and being maintained in their adjusted positions by nuts h' on the threaded ends of the rods. These springs yieldably support the gangs.

10 I, I designate clevises whose rear ends are related to the couplings G, G' respectively, so that they may be adjusted upon substantially vertical axes with relation to said couplings and held in adjusted position. In 15 the herein-exemplified form of the invention each clevis has rearwardly extending arms 38 and 39. These arms are arranged, respectively, above and below the adjacent sleeve 27, between the latter and the arms 21 20 and 22 of the adjacent coupling, and are pivotally mounted on the adjacent post 29. The clevises after being adjusted are fixedly secured to the couplings by suitable devices, as, for example, the bolts 40 extending 25 through laterally elongated slots 41 formed in the upper arms 21 of the couplings. The forward ends of the clevises I, I are connected by draft rods 42, 42 with other clevises I', I' having means whereby the forward ends of the draft rods are adjustable 30 side wise independently of their rear ends. The clevises I', I' are carried by the evener arches D, D', being preferably secured to the lower evener arches D', D' by the securing devices at 15 and 19, hereinbefore mentioned. For the described side wise adjustment of the forward ends of the draft rods each clevis I', I' is preferably provided with a series of spaced apertures 43 and the forward ends of the draft rods 42, 42 are preferably turned down as shown at 42^a, 42^a to enter any one of said apertures and to be readily removable therefrom.

It will be noted that when the clevises I, 45 I and draft rods 42, 42 are in the position shown in Fig. 2, the line of draft will be such as to make the gang beams work parallel to each other, the draft rods being in direct line with the longitudinal axis of said beams and that the beams may be thrown into extreme in or out position, or to predetermined intermediate positions by proper adjustment of the rear clevises I I and forward ends of the draft rods in the front 50 clevises I' I'; and that the provision for independent lateral adjustment of both the rear clevises and the forward ends of the draft rods permits of a very wide range of adjustment of the beams relatively to each other, the arrangement also being such that the beams may be fixed in any one of a number of positions between the extremes of their adjustment. Thus, assuming that the beams are to be set in their extreme positions 55 toward each other, the clevises I I are ad-

justed to the extreme inner positions defined by the inner ends of the slots 41 and the outer ends of the draft rods are inserted in the apertures at the outer ends of the clevises I' I'; while if it is desired that the beams 70 shall occupy their extreme outer positions of adjustment, the clevises I I are adjusted to positions defined by the outer ends of the slots 41 and the ends of the draft rods are inserted in the apertures at the inner ends 75 of the clevises I' I', and by varying laterally either the positions of the clevises I I or the positions of the forward ends of the draft rods, or of both the clevises I I and front ends of the draft rods, the beams will be 80 caused to swing relatively to each other in a direction according with the direction and such adjustment and to an extent determined in part by the extent of such adjustment and in part by whether the adjustment is of both 85 the rear clevises and the front ends of the draft rods or is of the rear clevises or front ends of the draft rods, only. Moreover, it will be noted that the clevises I I are adjustable independently of each other and 90 that the draft rods are adjustable independently of each other, whereby the beams are independently adjustable on their vertical axes whereby either may be set to work in any position within the extremes of its adjustment without requiring that the other shall be set in a like or corresponding position, it being expedient in some cases to work with one beam in its outward position of adjustment while the other occupies some 95 other position, for example.

Each gang beam F, F' is preferably hollow and of square or other suitable polygonal form in cross section. Their forward ends are provided with sleeves f, f', which are 105 externally round and internally of shape conforming to the external shape of the beams. These sleeves are interposed between the beams and gang couplings G, G', and may be turned axially in the couplings, 110 and hence it follows that the square beams, which are fixed to the sleeves,—may be turned axially with relation to said couplings. Preferably each sleeve, as most clearly shown in Figs. 4, and 5, is formed of two complementary members 44 and 45 having flanges 44^a and 45^a at their forward ends and provided internally with projections 46. The projections 46 enter recesses 47 in the beams and hold the sleeves against turning upon 115 the beams. The couplings G, G' are mounted on said sleeves and for this purpose they are provided rearwardly of their bifurcated forward ends with tubular portions 48 which preferably are split longitudinally for convenience in mounting them upon the sleeves f, f'; said portions 48 having suitable provision, such, for example, as the ears 49 and bolts 50, for clamping their sections together tightly around the sleeves. The 120 125 130

flanges 44^a and 45^a of the sleeve-sections engage the surfaces of the couplings within the bifurcated portions of the latter, and prevent longitudinal displacement of the sleeves, in one direction. Longitudinal displacement of the sleeves in the opposite direction may be prevented by forming the rear ends of the members 44 with lugs 51 to engage the rear ends of the couplings.

10 The rear ends of the gang beams are provided with couplings J, J' whose forward ends, 52, are fixedly secured thereto, said forward ends being preferably split longitudinally and drawn tightly to place around the beam by suitable devices, as, for example bolts 53, as shown. The rear ends of these couplings are bifurcated, each having upper and lower arms 54 and 55. Between these arms of each coupling J, J' a cross head is 15 pivotally mounted. These cross heads are marked K, K. As clearly shown at the left hand side of Fig. 3, it being understood that the corresponding portions shown in elevation at the right hand side in said figure are 20 of like construction, the upper arms 54 of the couplings J, J' have conical sockets 55' like those of the upper ends of the front couplings, while the lower arms 55 have tapered openings 56 provided with removable internally and externally tapered hollow plugs 57 25 with protruding squared ends 57^a, similar to the openings 24 and pivot bearings 25 of the front couplings. The sockets 55' and plugs 57 form bearings for projections 58 and 59 30 which extend upwardly and downwardly from the cross heads and have conical ends which are seated in said sockets and plugs, said projections thereby forming pivots by which the cross heads may be swung on vertical axes within the rear couplings. These 35 pivots preferably are hollow and suitable devices as bolts, 60, for example extend through the same and hold the parts together, this formation also providing for 40 the taking up of wear in the contacting surfaces while the removable plugs permit of 45 easy assemblage.

At one end of each cross head K, K there are two chambers 65 and 66 which are open 50 at top and bottom. Each of these chambers is wider at one side than the other, the wider side of one being adjacent to the narrower side of the other, as shown clearly in Fig. 2. The division wall between these chambers is 55 also divided transversely of the cross head by apertures 67 and 68 (as shown at the left hand side of Fig. 3) which pass through the sides of the cross head, as shown at 67^a and 68^a at the right hand side of Fig. 3. Preferably, the division wall referred to is formed by three spaced cross ribs, 69, which extend diagonally and are arranged one above another, the spaces between the ribs registering with the openings 67 and 68 at the opposite 65 sides of the cross head. Either of the cham-

bers 65, 66 is adapted to receive a standard 61 having a suitable soil treating element, as the shovel 62, for example, and either of said chambers is likewise adapted to receive a block 70 having an inclined surface, the standard being mounted in one chamber and the block in the other chamber. Provision for adjusting the standard and its soil treating element longitudinally of the cross-head—i. e. transversely of the implement—is thereby made. Wedge keys 71, (Figs. 2 and 3) each of which has a tapered face 71^a corresponding to the taper of the blocks and a plane face 71^b corresponding to the plane surface of the standards, are inserted through either of the openings 67^a and 68^a and extend through the apertures 67 and 68, the tapered surfaces of the keys engaging the tapered surfaces of the blocks and the plane surfaces of the keys engaging the plane surfaces of the standards, said keys in conjunction with the blocks thereby effectively holding the standards in adjusted position, while permitting the latter readily to be adjusted vertically within or wholly removed from the 90 chambers.

Each of the wedge keys 71 preferably has a threaded outer end 71^c, Fig. 2, which receives a nut 72. The nuts are against the cross heads and by turning them the wedge 95 keys may be drawn to place or slackened.

The other end of each cross head has a cylindrical split socket 74 the opening through which extends in the general direction of the length of the machine. This socket is provided with a longitudinally-divided sleeve formed of complementary members 75, 75 shown in detail in Fig. 3 formed to provide an internal angular opening to receive the forward end of an extension arm 105 63, which is removable therefrom and adjustable longitudinally therein, and is held in position by suitable means such, for instance, as clamping bolts 74^a extending through lips or flanges 76 of the socket. 110 The sleeve formed by said members 75, 75 is externally round and the socket 74 is internally of like shape, whereby said sleeve may be turned within the socket to thereby pivotally adjust the standard sidewise.

Removable from and longitudinally adjustable upon the extension arms 63 are standard brackets L, L. Each of these brackets, as shown in Figs. 1 and 6, has a longitudinal opening 77 through which the extension arm 63 extends, a chamber 78 through which the standard 61^a extends and a chamber 79 for a wedge key 80. The chamber 78 is inclined to the vertical to hold the standard at a corresponding inclination, 125 as best shown in Fig. 1, and is arranged on one side of the opening 77 while the chamber 79 is of tapered conformation and is on the other side of the opening 77. The wedge block 80 and a set screw 81 serve to clamp 130

the extension arms and standards in their adjusted positions. In the herein exemplified arrangement the wedge blocks engage the extension arms while the set screws engage the standards, but this position of the parts may be reversed, as is obvious.

Provision is also made for a removable standard 85 at the center of each cross head, each standard having a shovel 62^b or other suitable soil treating element. In the exemplified arrangement the cross head is provided with a rearwardly-extending lug 82 having upper and lower lips or flanges 83 and the cross head has lips or flanges 84 at its top and bottom adjacent to the forward ends of the flanges 83. The standard 85 has a forwardly extending end which lies alongside the lug 82, within the space between the lips or flanges 83 and projects into the space between the lips or flanges 84, being held from vertical displacement by said flanges. Suitable means, such as a bolt 86 extends through the lug 82 and forwardly extending end of the standard 85 and secures these parts together.

87 designates parallel rods whose front ends are attached to rearward projections 88 from the sleeves 27 and whose rear ends are pivotally attached by knuckles 89 to lugs 90 projecting from the cross head.

The rear ends of the upper arms 54 of the rear gang couplings J, J' are preferably formed with circular plates 91, which form members of dial couplings for adjustably connecting the handles M pivotally to the arms 54, the other members of the dial couplings being designated 92. Such connections are old and well known and need not be further referred to particularly, as they form no essential part of the invention.

The saddle A for the axle is a casting having two openings 93 and 94 extending cross wise of the beam B (see Fig. 1). These openings form bearings for the portions 10, 45 10 of the axle members, respectively. Each of these bearings has at one of its ends a chamber 95 (see Fig. 7) with inner and outer walls 96 and 97 and each axle member 10 is provided with a collar 98 (Fig. 1) 50 which is secured thereto by suitable means, as a set screw 99, for example. These collars respectively fit in the chambers 95 and coact with the walls 96 and 97 of the latter to prevent accidental movement of the axle 55 members 10 from the positions to which they have been adjusted. The walls 97 of the chambers 95 are cut away at 100 to permit the collars 98 to be inserted into said chambers.

Having now described the invention what I believe to be new and desire to secure by Letters Patent, is:—

1. A soil tillage implement comprising a beam for supporting the tillage element, and mounted to have lateral pivotal move-

ment, and draft means connected to the beam, the draft means including an intermediate member whose front and rear ends are adjustable laterally relatively to each other and to the beam and are maintained against accidental displacement from their adjusted positions. 70

2. A soil tillage implement comprising beams for supporting the tillage elements, and mounted to have independent lateral pivotal movement, and draft means including intermediate elements respectively having connection with the beams and whose front and rear ends are adjustable laterally relatively to each other and to the beams 75 30 and are maintained against accidental displacement from their adjusted positions.

3. A soil tillage implement comprising beams for supporting the tillage elements, and mounted for lateral pivotal movement, 85 and draft means comprising rear clevises having connection with the beams, front clevises, and intermediate members respectively connecting the front clevises with the rear clevises, the clevises being adapted to 90 permit the front and rear ends of the intermediate members to be adjusted laterally relatively to each other and to the beams and to be held against accidental displacement from their adjusted positions. 95

4. A soil tillage implement, comprising beams for supporting the tillage elements, and mounted for lateral pivotal movement, and draft means including sets of front and rear clevises and intermediate members, the 100 rear clevises having connection with the beams and each intermediate member connecting a front clevis with the corresponding rear clevis, one clevis of each set being mounted for pivotal adjustment on a substantially vertical axis and having means for fixedly securing it in its adjusted position with relation to the beam and the other clevis having means whereby the adjacent end of the intermediate member is adjustable laterally relatively to the opposite end 110 of said member and is maintained against accidental displacement from its adjusted position.

5. A soil tillage implement, comprising 115 beams for supporting the tillage elements, and mounted for lateral pivotal movement, and draft means including sets of front and rear clevises and intermediate members, the rear clevises having connection with the 120 beams and being mounted for pivotal adjustment on substantially vertical axes relatively to the beams and to the front clevises, and the connections between the rear clevises and the beams including means by which the rear clevises are secured fixedly in adjusted position.

6. A soil tillage implement comprising 125 beams for supporting the tillage elements, and having their forward ends provided 130

with couplings which are mounted for pivotal movement laterally, laterally adjustable clevises connected to said couplings and having means for fixedly securing them in adjusted position, intermediate members whose rear ends are connected to said clevises and are thereby adjustable laterally with reference to the beams, and clevises to which the forward ends of the intermediate members respectively are connected, the last named clevises being adapted to permit lateral adjustment of the forward ends of the intermediate members independently of the lateral adjustment of the rear ends of the same.

7. A soil tillage implement comprising beams for supporting the tillage elements, and having their forward ends provided with couplings which are mounted for pivotal movement laterally and have parts projecting forward of their axes, clevises mounted for lateral pivotal adjustment relatively to said couplings, means for fixing the clevises to the forwardly projecting parts of the couplings, draft elements whose rear ends are carried by said clevises and are thereby adjustable laterally with reference to the beams, and clevises to which the forward ends of the draft elements respectively are connected, the last named clevises being adapted to permit lateral adjustment of the forward ends of the draft elements independently of the rear ends of the same, the forward ends of the draft elements and the forward clevises being operatively related to hold the former in adjusted positions.

8. A soil tillage implement, comprising beams for supporting the tillage elements, and having their forward ends provided with couplings which are mounted for pivotal movement laterally and have parts projecting forward of their axes, clevises mounted for lateral pivotal adjustment relatively to said couplings, means for fixing the clevises to the forwardly projecting parts of the couplings, draft elements whose rear ends are carried by said clevises and are thereby adjustable laterally with reference to the beams, and clevises to which the forward ends of the draft elements respectively are connected, the last named clevises each having a series of apertures severally adapted to receive the ends of the adjacent draft element and to permit lateral adjustment of the forward end of said element independently of the adjustment of the rear end of the latter.

9. A soil tillage implement comprising a pole, a pair of clevises supported from the pole, draft elements whose forward ends are operatively related to said clevises, respectively, said clevises being adapted to permit lateral adjustment of the forward ends of the draft elements, pivotally movable beams for supporting the tillage elements, and con-

nections between the beams and the rear ends of the draft elements, said connections including clevises to which the rear ends of the draft elements are connected, the latter clevises being adapted to permit lateral adjustment of the rear ends of the draft elements independently of the lateral adjustment of the forward ends of the same.

10. A soil tillage implement comprising a pole, a pair of clevises supported from the pole, draft elements whose forward ends are operatively related to said clevises, respectively, said clevises being adapted to permit lateral adjustment of the forward ends of the draft elements, beams for supporting the tillage elements, and connections between the beams and the rear ends of the draft elements, said connections including couplings secured to the forward ends of the beams and mounted for lateral pivotal movement and clevises which are mounted for lateral pivotal adjustment relatively to the couplings and are provided with means for fixing them in adjusted positions to said couplings, the rear ends of the draft elements being connected to the last-mentioned clevises.

11. A soil tillage implement comprising a pole, clevises carried from the pole, each of said clevises having a plurality of apertures arranged in different vertical planes, beams respectively arranged rearward of said clevises, said beams being adapted to carry tillage elements and having their forward ends mounted for lateral pivotal movement, and draft elements whose rear ends are respectively connected to said beams, the connection embodying means by which the rear ends of said draft elements are adjustable laterally relatively to the beams and are maintained in their adjusted position, the forward ends of said draft elements engaging the first mentioned clevises, respectively, and being adjustable from one aperture to another thereof.

12. A soil tillage implement comprising a pole, supports depending from opposite sides thereof, clevises carried by the depending portions of the supports, each of said clevises having a plurality of apertures arranged in different vertical planes, beams respectively arranged rearward of said clevises, said beams being adapted to carry tillage elements and having their forward ends mounted for lateral pivotal movement, draft elements, and connections between the rear ends of the draft elements and the beams, the connection embodying clevises which are mounted for pivotal adjustment on substantially vertical axes and are provided with means for fixing them in adjusted position, the forward ends of said draft elements engaging the first mentioned clevises, respectively, and being adjustable from one aperture to another thereof.

13. A soil tillage implement comprising a beam, a coupling secured thereto and projecting forward thereof, an approximately vertical pivot for the coupling, a clevis 5 mounted for pivotal adjustment on a substantially vertical axis, means for fixing the clevis in its adjusted position with relation to the coupling, and a draft element connected to said clevis.
- 10 14. A soil tillage implement comprising a beam, a coupling secured thereto and projecting forward thereof, a clevis, means whereby the clevis and coupling are relatively movable on a substantially vertical 15 common axis, means for connecting the clevis and coupling fixedly together when thus adjusted, and a draft element connected to the clevis.
15. A soil tillage implement comprising a beam for supporting a tillage element, said beam being mounted for movement upon substantially vertical axes and draft means, comprising forward and rear clevises and an intermediate member connecting the clevises, the rear clevis being mounted for lateral 20 pivotal adjustment relative to the beam and means for securing it in adjusted position.
16. A soil tillage implement comprising a beam, a coupling secured thereto and projecting forward thereof, an approximately vertical pivot for the coupling, the coupling having a member which extends forward of the pivot, a clevis mounted for pivotal adjustment laterally around said pivot and 25 contiguous to said member, means for securing the clevis in adjusted position to said member, and a draft element connected to said clevis.
17. A soil tillage implement comprising a beam provided with a coupling, an approximately vertical pivot for the coupling, a clevis mounted for adjustment around said pivot relatively to the coupling, the coupling and clevis having juxtaposed members one 30 of which is provided with a fastening means and the other with an arcual slot into which the fastening means extends, and a draft element connected to said clevis.
18. A soil tillage implement comprising a beam, a coupling secured thereto and provided with forwardly extending arms with a space between, an approximately vertical pivot for the coupling arranged between said arms, one of the arms extending forward of 35 the pivot and having an arcual opening extending transversely of the implement, a clevis arranged contiguous to said arms and mounted for pivotal adjustment laterally around said pivot, means for fastening the clevis in its adjusted position to the forwardly extending portion of the arm of the coupling, said means including an element which extends through said arcual opening, and draft mechanism connected to said 40 clevis.
19. A soil tillage implement comprising carrying wheels, an axle, beams adapted to carry tillage elements, couplings carried by said beams, connections between the couplings and the axle, and draft mechanism 45 having connection with the couplings, the connections between the couplings and the axle including members which are open along their forward edges and spaced vertically rearwardly projecting portions, the forward members receiving the axles between them and being provided with elements which are separate therefrom and conjointly therewith form sleeves which are mounted on the axle, approximately vertical pivots 50 for the couplings extending between the rearwardly projecting portions of sleeve members, said sleeves and pivots being relatively adjustable in the direction of the length of the pivots, and means for securing 55 them when adjusted.
20. A soil tillage implement, comprising carrying wheels, an axle, sleeves mounted on said axle and each having members projecting therefrom and provided with an approximately vertical space between them, beams 60 adapted to carry tillage elements, couplings projecting forward from said beams, stationary pivots for said couplings, extending through the space between members of said sleeves, the pivots and sleeves being relatively adjustable in the direction of the length of the pivots, fastening means adapted to clamp the sleeve members tightly 65 around the pivots, and draft mechanism having connection with said couplings.
21. A soil tillage implement, comprising carrying wheels, an axle, sleeves mounted on said axle and having spaced members projecting therefrom, beams adapted to carry 70 tillage elements, couplings projecting forward from said beams and having spaced arms provided with bearings, pivots extending between the members of the sleeves and having their ends engaged with the bearings 75 in the coupling arms, and means whereby the members of the sleeves are fixed with relation to said pivots, and draft mechanism 80 having connection with said couplings.
22. A soil tillage implement, comprising carrying wheels, an axle, sleeves mounted on said axle and having spaced members projecting therefrom, beams adapted to carry 85 tillage elements, couplings projecting forward from said beams and having spaced arms provided with internally tapered sockets aligned with the spaces between the members of the sleeves, one socket of each coupling being removable, pivots extending 90 between the members of the sleeves and comprising sleeves having tapered ends seated in the pivot sockets and bolts extending through said sleeves and arms, and means whereby the first-mentioned sleeves are fixed 95 with relation to said pivots, and draft mechanism 100 having connection with said couplings.
23. A soil tillage implement, comprising carrying wheels, an axle, sleeves mounted on said axle and having spaced members projecting therefrom, beams adapted to carry 105 tillage elements, couplings projecting forward from said beams and having spaced arms provided with internally tapered sockets aligned with the spaces between the members of the sleeves, one socket of each coupling being removable, pivots extending 110 between the members of the sleeves and comprising sleeves having tapered ends seated in the pivot sockets and bolts extending through said sleeves and arms, and means whereby the first-mentioned sleeves are fixed 115 with relation to said pivots, and draft mechanism 120 having connection with said couplings.
24. A soil tillage implement, comprising carrying wheels, an axle, sleeves mounted on said axle and having spaced members projecting therefrom, beams adapted to carry 125 tillage elements, couplings projecting forward from said beams and having spaced arms provided with internally tapered sockets aligned with the spaces between the members of the sleeves, one socket of each coupling being removable, pivots extending between the members of the sleeves and comprising sleeves having tapered ends seated in the pivot sockets and bolts extending through said sleeves and arms, and means whereby the first-mentioned sleeves are fixed 130 with relation to said pivots, and draft mechanism having connection with said couplings.

mechanism having connection with said couplings.

23. A soil tillage implement comprising carrying wheels, an axle, sleeves mounted on said axle and having spaced members projecting therefrom, beams adapted to carry tillage elements, couplings projecting forward from said beams and having spaced arms provided with internally tapered sockets alined with the spaces between the members of the sleeves, one socket of each coupling being removable, pivots extending through the spaces between the members of the sleeves and comprising sleeves having tapered ends seated in said sockets, and bolts extending through the pivots sleeves and arms, the projecting members of the first-mentioned sleeves being divided on lines which intersect their said openings, fastening means for clamping the walls of the first-mentioned sleeve members fixedly around the sleeves of the pivots, and draft mechanism having connection with said couplings.
24. A soil tillage implement comprising carrying wheels, an axle, beams adapted to carry tillage elements, couplings carried by said beams, said couplings having upper and lower arms, spaced apart, clevises adjacent to said couplings, the clevises being pivotally adjustable on approximately vertical axes relatively to the couplings, sleeves mounted on the axle, approximately vertical pivots for said couplings, means for fixedly securing said sleeves to the pivots, and draft elements connected to said clevises.

25. A soil tillage implement comprising carrying wheels, an axle, beams adapted to carry tillage elements, couplings carried by said beams, said couplings having upper and lower arms, clevises adjacent to said couplings, the clevises being pivotally adjustable on approximately vertical axes relatively to said couplings and provided with means for fixedly securing them in adjusted

positions, sleeves mounted on the axle and having rearwardly projecting spaced members, approximately vertical pivots extending between said sleeve members, the arms of the couplings having bearings which engage the ends of the pivots and the couplings being thereby movable on approximately vertical axes around said pivots, means for securing the rearwardly projecting members of the sleeves to the pivots, and draft elements connected to said clevises.

26. In a tillage implement, a beam having a coupling connected to one of its ends, said coupling having upper and lower arms, a clevis, means by which the coupling and clevis are relatively movable pivotally upon a common axis, and means at one side of said axis for securing the clevis in selected positions to the coupling.

27. In a tillage implement, a beam having a coupling connected to one of its ends, said coupling having upper and lower arms, a pivot to which the arms are connected to swing relatively thereto, a clevis connected to said pivot and adjustable thereabout, and means at one side of the pivot for securing the clevis adjustable to the coupling.

28. In a tillage implement, a beam having a coupling connected to one of its ends, said coupling having upper and lower arms, a pivot to which the arms are connected to swing relatively thereto, one of said arms having a lateral extension at one side of the pivot, a clevis connected to said pivot and adjustable thereabout, and means for securing the clevis in selected positions to the lateral extension.

In testimony whereof I have hereunto set my hand in presence of two subscribing witnesses.

CHARLES T. RAY.
